AUTOMOBILE WHEEL COVER

Allan E. Kornmiller, Birmingham, Mich., assignor to Chrysler Corporation, Highland Park, Mich., a corporation of Delaware

Filed May 27, 1960, Ser. No. 60,773

Term of patent 7 years

(Cl. D14—30)

Fig. 1 is a front elevational view of an automobile wheel cover showing my new design; and

Figs. 2 and 3 are sectional views taken on the lines 2—2 and 3—3, respectively, of Fig. 1.

I claim:

The ornamental design for an automobile wheel cover, substantially as shown.
